UNITED STATES PATENT OFFICE.

ARTHUR H. FETTERS, OF OMAHA, NEBRASKA.

BOLSTER.

No. 853,545.

Specification of Letters Patent.

Patented May 14, 1907.

Application filed January 6, 1906. Serial No. 294,834.

To all whom it may concern:

Be it known that I, ARTHUR H. FETTERS, residing at Omaha, in the county of Douglas and State of Nebraska, have invented certain new and useful Improvements in Bolsters, of which the following is a full, clear, and exact description, such as will enable others skilled in the art to which it appertains to make and use the same.

10 This invention relates to bolsters and the like. One of the objects thereof is to provide a simple practical bolster having a maximum of lightness, stiffness and strength.

Another object is to provide a bolster of 15 the above type in which the parts so interlock and fit into one another as to reduce the stress upon the retaining devices holding them together to a minimum.

Other objects will be in part obvious and 20 in part pointed out hereinafter.

The invention, accordingly, consists in the features of construction, combinations of elements and arrangement of parts which will be exemplified in the embodiment there- 25 of hereinafter described and the scope of the application of which will be indicated in the following claims.

In the accompanying drawings, wherein is shown one of the various possible embodiments of my invention, Figure 1 is an elevation thereof, showing its relation to a truck. Fig. 2 is a perspective view of a kingpost. Fig. 3 is a side elevation of an end casting. Fig. 4 is a perspective view of the bolster, 35 certain parts being broken away in order to show the construction more clearly.

Similar reference characters refer to similar parts throughout the several views of the drawings.

40 This invention will be most readily grasped if it be borne in mind that a car bolster, by reason of its being necessarily subjected to a considerable normal load and to severe wrenching stresses during its use, is generally made of heavy construction, thus wasting material and diminishing the lightness of the truck. This and other defects are done away with, without sacrifice of stiffness or strength, in constructions of the nature of 45 that hereinafter described.

Referring now to the accompanying drawings, there is shown in Fig. 1 a bolster mounted upon elliptic springs 1 which rest upon a spring plank 2 suspended as by swing-hangers 3 from transoms 4. The latter parts are secured to the side bars 5 of the truck, from

which the load is transmitted in any desired manner, as by pedestals 6, to the axle boxes 7 and thence through the wheels 8 to the rails. The latter of the above recited parts are 60 shown in dotted lines only, as they form, in themselves, no part of the present invention, and a detailed showing thereof would merely confuse the disclosure.

The bolster which embodies the dominant 65 features of this invention comprises a kingpost 9, to the upper and lower portions of which are secured pairs of angle members 10 and 11. It may here be noted that the term "angle member," or its equivalent, is used 70 throughout the following claims to denote a member provided with longitudinal flanges or webs angularly disposed with reference one to another. Members 10 and 11 converge in vertical planes, as best shown by 75 reference to Fig. 4 of the drawings, and terminate at each lateral end of the bolster within end castings 12, the construction of which will hereafter be described in detail.

The kingpost 9 comprises an upper portion 80 13 and a lower portion 14 connected upon their front and rear edges, with reference to the position of the bolster upon the truck, by webs 15 and 16 respectively. The upper and lower portions are also connected by a tubular 85 casing 17 adapted to inclose and guide the lower end of the kingpin which projects downwardly through the center plate 18 in the well-known manner. From casing 17, webs 19 and 20 extend respectively laterally 90 and to the front and rear, the latter webs being connected with webs 15 and 16, as best shown in Fig. 2 of the drawings. The upper and lower portions of the kingpost are provided adjacent their front and rear edges 95 with depressed or offset portions, within which the horizontal flanges of the angle members rest, thus permitting the surfaces thereof to lie flush with the upper and lower surfaces of the post. 100

The end casting 12, with reference to which it may here be noted that the term "casting" is used in a broad sense as covering any metallic member, irrespective of its method of manufacture, comprises a base- 105 portion 21 extending beneath the lower angle members 11 and flanged at its ends so as to embrace the same, as best shown at 22 in Fig. 3 of the drawings. The upper portion of the end casting forms a support for the side bearing of the truck and is connected with the base by a longitudinal web 23 and 110

lateral webs 24, the latter being provided with outwardly-disposed flanges 25 adapted to rest upon the angle members 10.

Additional stiffness is afforded the bolster 5 by channel sections 26 disposed at each side of the kingpost between the angle members 10 and 11 and having their flanges riveted thereto, and plates 27 tying the lower flanges of the angle members 11 one to another.

10 The entire bolster, with the exception of the end castings 12 is preferably covered by a plate or sheet 28 perforated for the kingpin at 29 and riveted to the kingpost and angle members 10.

15 It will be understood that rivets or other retaining devices are used throughout the entire above-described structure wherever necessary, although, on account of the interlocking disposition of the several parts the stress 20 upon these members is reduced to a minimum.

25 The action of the above-described embodiment of my invention, which should be in large part obvious from the above description, is as follows: Assuming the load to be applied through the center plate 18, the same is transmitted through the angle members 10 and 11 to the springs 1, the entire device acting as a truss in which the kingpost forms a strut or spacing member and the upper and lower chords are formed by the angle members 10 and 11 respectively. Inasmuch as the latter members are fitted within and securely tied to the end castings, and no relative movement due to thrust or pull thereof can take place at this point, the bolster can fail only by buckling of the upper members or tearing out or apart of the lower chord, as above defined. The chance of buckling is substantially eliminated, not only by the flanged 35 conformation of the angle members, but by the auxiliary stiffening devices 26 and the plate 28. The lower members, moreover, on account of their connection not only with the kingpost, the plates 27 and the channel 40 members 26, but by the way in which they are tied into the end castings, cannot under any conditions of use be torn out of their original position. Thus, as the chance of the kingpost collapsing is, by reason of the 45 flanged construction, negligible, the bolster will preserve its original form and act as a unit under the most severe conditions of use.

50 It will thus be seen that I have provided a device which accomplishes the objects of my invention in a most simple and efficient manner and which is of inexpensive and light construction and gains its high degree of efficiency by reason of the careful disposition of the metal employed, whereby all parts of 55 each member are used to their full value with, of course, the proper factor of safety.

60 As many changes could be made in the above construction and many apparently widely different embodiments of my invention could be made without departing from

the scope thereof, I intend that all matter contained in the above description or shown in the accompanying drawings shall be interpreted as illustrative and not in a limiting sense. I desire it also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:—

1. In a bolster, in combination, central 80 spacing means, a pair of members at each side of said means, the members of each pair being secured respectively to the upper and lower portions thereof and extending laterally therefrom, means connecting the ends of 85 said members in pairs and the pairs one to another at each end of the bolster, and a plate or sheet extending over said bolster and secured thereto.

2. In a bolster, in combination, a plurality 90 of laterally-disposed angle members, means holding the ends of said members in fixed relation one to another at each end of the bolster, means adjacent the center of the bolster secured to each of said angle members, 95 and a plate or sheet extending over the bolster and secured thereto.

3. In a truck, in combination, a plurality 100 of laterally-disposed angle members, and integral end members provided with flanges 100 between which the ends of said first-mentioned members rest and adapted to support the side bearings of the truck.

4. In a bolster, in combination, a kingpost comprising an upper portion and a lower 105 portion, front and rear webs connecting said upper and said lower portions, a tubular portion connecting said upper and lower portions and adapted to inclose a kingpin, and a web extending from said tubular portion 110 to each of said front and rear portions.

5. In a bolster, in combination, central 115 spacing means, a pair of angle members at each side of said means, the members of each pair being positioned adjacent to the upper and lower portions thereof and extending laterally therefrom, means connecting the ends of said members in pairs, and the pairs one to another at each end of the bolster, and additional spacing means stretched between said members at each side of said central spacing means.

6. In a bolster, in combination, central 125 spacing means, a pair of angle members at each side of said means, the members of each pair being positioned adjacent to the upper and lower portions thereof and extending laterally therefrom, means connecting the ends of said members in pairs and the pairs one to another at each end of the bolster, and 130

additional spacing means stretched between said members at each side of said central spacing means, said members projecting from said central spacing means toward said

5 second-mentioned means.

7. In a bolster, in combination, central spacing means, a pair of angle members at each side of said means, the members of each pair resting respectively against the upper and lower portions thereof and extending laterally therefrom, and an end member at each end of the bolster provided with flanges between which the ends of said members are secured.

15 8. In a bolster, in combination, a kingpost comprising an upper portion and a lower portion, front and rear webs connecting said upper and said lower portions, and a tubular portion connecting said upper and lower portions and adapted to inclose a kingpin, a pair of members at each side of said kingpost, the members of each pair resting respectively against the upper and lower portions thereof and extending laterally therefrom, and means connecting the ends of said members in pairs and the pairs one to another at each end of the bolster.

25 9. In a bolster, in combination, a kingpost comprising an upper portion and a lower portion, front and rear webs connecting said upper and said lower portions, and a tubular

portion connecting said upper and lower portions and adapted to inclose a kingpin, a pair of angle members at each side of said kingpost, the members of each pair resting respectively against the upper and lower portions thereof and extending laterally therefrom, and means connecting the ends of said members in pairs and the pairs one to another at each end of the bolster.

35 10. In a bolster, in combination, a kingpost comprising an upper portion and a lower portion, front and rear webs connecting said upper and said lower portions, and a tubular portion connecting said upper and lower portions and adapted to inclose a kingpin, a pair of angle members at each side of said kingpost, the members of each pair resting respectively against the upper and lower portions thereof and extending laterally therefrom, means connecting the ends of said members in pairs and the pairs one to another at each end of the bolster, and a sheet or coverplate extending over and secured to the bolster.

40 50 In testimony whereof I affix my signature, in the presence of two witnesses.

ARTHUR H. FETTERS.
